[57] ABSTRACT

The invention is directed to a fire-starting device for conducting an individual's breath to specific areas of flowing or smoldering embers to enhance the starting of a fire. The device consists of a cylindrical tube with a mouth piece at one end and a nozzle at the other end to direct the user's breath onto the embers. Disposed within the device is a valve which permits the user's breath to be directed through in the direction of the nozzle end but excludes the passage of air or other gases in the opposite direction.

FIG. 1

FIG. 2

FIG. 3

CAMPFIRE STARTING DEVICE

BACKGROUND OF THE INVENTION

Hunters, woodsmen and others who camp out have a continuing requirement to build fires out-of-doors for warmth and for cooking. The normal procedure in kindling such a fire calls for the use of locally available materials such as twigs, sticks, leaves, logs, etc., as fuel for their fires. These fuels are often damp or green if freshly broken from their parent plant and do not burn readily. Therefore, considerable fanning and/or blowing on embers is required to develop a full flame fire capable of providing sufficient heat for cooking or warmth. Fanning a fire is a sporadic means of developing a full flame fire and produces only general effectiveness. Blowing on an ember's bed with one's mouth is very effective; however, since an individual's mouth must be in close proximity to the ember's bed, if the desired results are to be achieved, there is a risk to the individual performing the blowing on the ember's bed whereby facial burns or eye damage may be incurred due to embers, smoke or ashes being accidentally blown back into the facial area. The current invention provides an inexpensive device that is highly effective in directing blown breath on specific areas of glowing embers to enhance the starting of full flame fires. The present invention is so constructed that an individual using the device is not threatened with injury caused by a blow-back of glowing embers, smoke or ashes into his facial area or by the inhalation of super-heated air from the area of the ember's bed he is attempting to kindle. These features are particularly important to the numerous outdoorsmen who have definite requirements as well as personal desire to kindle fires effectively and safely.

SUMMARY OF THE INVENTION

This invention relates to a new and unique firestarting device for the kindling of full flame fires from glowing embers and smoldering fires. An important object of this invention is to provide a safe and effective means for the kindling of fires for those individuals who desire to kindle fires by blowing upon glowing embers and/or smoldering fires. Another object of the present invention is to provide a device adapted for optimum utilization of an individual's breath on specific areas of a glowing ember's bed to enhance the kindling of a starting fire or to develop a smoldering fire into full flame. Yet another object of the present invention is to provide a device to enhance the kindling of fires which is easily portable, i.e., pocket size. Further, another object of the present invention is to provide a device that will prevent the inhalation of super-heated air from the vicinity of glowing ember's beds or smoldering fires by an individual who is blowing on said beds of fires in an effort to develop them into full flame.

These and other objects are accomplished according to the present invention which comprises a cylindrical tube of approximate arm's length which is fitted on one end with a mouthpiece and on the other end with a discharge piece or nozzle. Within the passages of this assembly there is contained a one-way valve which permits air or breath flow only in the direction from the mouthpiece to the nozzle.

Other objects and many of the attendant advantages of this invention will be readily appreciated as the same

becomes better understood by reference to the following detailed descriptions when considered in connection with the accompanying drawings wherein:

FIG. 1 is a preferred embodiment of the invention.

FIG. 2 is an exploded view of the preferred embodiment of the mouthpiece and valve assembly.

FIG. 3 is a cross-sectional view of the mouthpiece and valve assembly.

DESCRIPTION OF PREFERRED EMBODIMENTS

In FIG. 1 there is shown a preferred embodiment of the invention adapted for reduced storage space, easy portability and pocket size. The device is comprised of a tube 1 with a nozzle assembly 2 on one end and on the other end a tubular duct 3 to which is attached a mouthpiece 4. The tube 1 is a thin-walled flexible tube of approximately an arm's length and an inside diameter of approximately 5/16 inch. One end of the tube 1 is slipped over the shank end of the nozzle assembly 2 and frictionally secured thereto by the contractile force of the flexible tube 1 over the larger diameter of the nozzle assembly 2. The nozzle assembly is of a telescopic design with its extreme end member wedge-shaped and with a plurality of holes through which the air or breath is discharged.

The end of tube 1 remote to the discharge end is frictionally secured to tubular duct 3 over whose one end it is slipped. The other end of tubular duct 3 is press-fitted to mouthpiece 4. Both the tubular duct 3 and the mouthpiece 4 are made of high-density polyethylene or other suitable material. Reference now is made to FIG. 3; there is shown a partial sectional view of the mouthpiece 4 whose end in cooperation with an elastomeric disc 5 and a disc constraining cage 6 comprise a simple one-way flow valve. In assembly, the cage 6, made of high density polyethylene or other suitable material, is press-fitted circumferentially onto mouthpiece 4. The internal end of the mouthpiece 4 is perforated with a plurality of axially aligned holes to form a screen. The valve assembly is enclosed by tubular duct 3.

A description of usage and operation of this invention is made with reference to FIG. 1-3. To use the fire-starting-aid device, the telescopic nozzle assembly 2 is first extended to its full length, then the mouthpiece 4 is placed in the individual's mouth while the nozzle 2 is directed to the fire being started. The individual blows into mouthpiece 4 which communicates with nozzle 2 through duct 3, tube 1 and discharge piece 2. The action of blowing into mouthpiece 4 drives the elastomeric disc 5 away from the internal end of mouthpiece 4 and against cage 6. Air or breath flows through the side openings of cage 6 and through duct 3, tube 1 and discharge nozzle 2. The moderately fanned shape of the nozzle 2 spreads the effect of the discharging air or breath whereas the restrictive character of the plurality of discharge holes on the end of the nozzle 2 creates a build-up within the device to impart a jet effect and at the same time an evenness of distribution to the discharge. Any attempt to inhale through the mouthpiece 4 creates a pressure difference across the elastomeric disc 5 which is held in close proximity to the internal end of mouthpiece 4 by cage 6 thereby causing elastomeric disc 5 to be drawn tightly against the internal end of mouthpiece 4 and thus preventing withdrawal and inhalation of air from the device into the user's mouth, throat and lungs.

Whereas a preferred embodiment has been described, a consideration of the invention will suggest many possible variations. For example, the tube 1 in FIG. 1 may be rigid and of different material and dimensions; the one-way valve built into mouthpiece 4 may be of different design and disposed anywhere within the flow passages of the device. The discharge nozzle 2 may be a simple tube and it may be of any fire resistant material. Accordingly, the invention is to be construed as including all of the embodiments within the scope of the appended claims.

Having described this invention, what I assert as new and pray issuance of letters of patent for, is:

1. A device for use as an aid when starting a campfire or the like by discharging air at a desired location, said device comprising a rigid mouthpiece having a tubular passageway therethrough, said mouthpiece adapted to be held in the mouth of a user with air being blown through the passageway when the user exhales or blows through the passageway, an elongated tube connected to said mouthpiece at one end thereof, said tube being flexible throughout its length and forming a continuation of said passageway, and an elongated rigid nozzle

connected to the end of the tube remote from the mouthpiece, said nozzle being provided with a passageway forming a continuation of the passageway in the mouthpiece and flexible tube for discharge of air therefrom directly onto a desired point of a campfire, said nozzle having a length sufficient to enable the end thereof connected to the tube to be grasped and handled in a manner to position the other end into the desired location in a campfire with the grasping hand 10 spaced from the fire to reduce the possibility of burns, said nozzle being constructed of fire resistant material, said mouthpiece, tube and nozzle being oriented in compact relation for positioning in a garment pocket or the like and being light in weight to facilitate carrying thereof by backpacking campers or the like, said mouthpiece including a one-way valve assembly 15 therein to prevent the user from inhaling through the nozzle and tube, said nozzle including a sectional telescopically adjustable tube member, the outermost tube 20 member being laterally enlarged into fan-shaped configuration and having a plurality of apertures for discharge of air or breath.
